VENTRILLOQUIST'S DUMMY

Martha McCown, Phoenixia, N. Y.

Application July 31, 1937, Serial No. 156,614

6 Claims. (Cl. 46—126)

My invention relates to a new and improved toy ventriloquist's dummy.

One of the objects of my invention is to provide a toy which shall be durable in construction, 5 and which can be manufactured and assembled at low cost.

Another object of my invention is to provide a toy having simple and conveniently assembled means for manipulating the head of the dummy, 10 and also for manipulating the eyes and the lower jaw of the dummy, so that a child can readily manipulate the dummy.

Another object of the invention is to provide a device which can be made of simple and sturdy 15 parts, which can be readily assembled.

Other objects of my invention will be stated in the following description and drawings, which illustrate a preferred embodiment of the invention, it being understood that the above general 20 statement of the objects of my invention is intended merely to explain the same generally, but without limiting it in any manner.

Fig. 1 is a front elevation of the improved dummy, a representation of a part of the garment of the dummy having been omitted, and a 25 part of said figure being in section.

Fig. 2 is a sectional view, partially in elevation, on the line 2—2 of Fig. 1.

Fig. 3 is a rear elevation of Fig. 1, the garments 30 of the dummy having been omitted, and the representation of the back of the head of the dummy having been omitted, in order to show the interior construction of the parts of the head more clearly.

Figs. 4 and 5 are respectively sectional views 35 on the lines 4—4 and 5—5 of Fig. 3.

Fig. 6 is a detail sectional view, showing the assembly between the parts for manipulating the eyes and the lower jaw of the dummy, and the 40 post upon which the head of the dummy is mounted.

Referring particularly to Fig. 3, the body 9 of the doll has a rectangular opening therein. Said body 9 can be made of wood or any other suitable 45 material, and it can be made of several parts which can be suitably connected to each other, although it may be of integral construction, as shown in Fig. 3.

The lower end of the body 9 is provided with 50 perforated lugs 10. A member 8, made of suitable elastic material, is passed through the perforations of the lugs 10, and the ends of said elastic member 8 extend upwardly along the outer surfaces of the side walls of the body 9. 55 These upwardly extending legs of the elastic

member 8 are connected to the side walls of the body 9, by means of suitable fastening members 11. The member 8 can be made of suitable covered rubber cord or the like.

The legs of the dummy comprise upper portions 6 and lower portions 2. The upper leg portions are provided with eyes 7, which pass around the elastic cord 8. The lower leg portions are provided with feet 1. The upper leg portions 6 and the lower leg portions 2 are connected to each other by means of intermediate connecting members 3 which are located in suitable vertical slots of said members 2 and 6. Said connecting members 3 are connected to the leg portion 6 by means of pins 5, so that there is a rigid assembly 10 between the members 3 and 6. The members 2 are turnably connected to the members 3, by means of pivot pins 4.

A hollow post 16 passes turnably through the top of the body 9. Means are provided for preventing any longitudinal movements of the post 16 relative to the body 9. Such means can consist of a pin 17, fastened to the post 16.

The head 21 of the doll is located wholly above the top of the body portion 9, and the neck of 25 the head is provided with the usual socket, by means of which the head 21 is connected to the top of the post 16.

As shown in Fig. 5, and also in Fig. 2, the head of the dummy is provided with a movable jaw 30 portion 20, which is pivotally connected to the head of the doll by means of a pivot pin 22. This pivot pin 22 passes through jaw portion 20, and the ends of said pin are imbedded in the material of the head of the doll. Member 20 turns on 35 member 22.

In order to make the parts, the head of the doll may be made in two parts. The front part which is relatively stiff and hard and durable can have the pivot pin 22 connected thereto, and it 40 can also have the eye-assembly connected thereto.

The rear of the head of the doll may be completed, by using any suitable moldable construction.

As shown in Fig. 5, the movable jaw member 20 is provided with a member 23a, which extends inwardly from the rear of said jaw member 20. Said member 23a can be provided with an eye 23. A first wire or first manipulating member 28, has an upper bent portion 28a, which passes through said eye 23. Said member 28 is located within hollow post 16, and member 28 is moved vertically relative to said post. As shown in Fig. 6, the post 16 has a vertical slot 50 55

in its wall. The wire 28 has an exterior loop 27, or any other type of convenient fingerhold. Hence, by moving the loop 27 up and down, the jaw member 20 can be rocked, up and down.

5 The head of the doll is also provided with artificial eyes 23, which are mounted so that they can be moved up and down, and also from side to side.

Numerous forms of eye-assemblies are well known for this purpose.

10 I have shown suitable and improved means, including a lateral bar 29, having sockets or openings in which the artificial eyes 23 are partially located. The eyes 23 can turn freely in all directions, relative to the openings or sockets which are provided in the member 29. The member 29 is connected to the wall of the head 21, by means of a member 30 which is partially imbedded in the material of the head 21. The inner end of this member 30 is threaded, and a suitable nut 20 130 clamps the block 29 into position against the inner surface of the front wall of the doll.

The eyes 23 have inwardly directed members 24 suitably connected thereto. These inwardly extending and rigid members 24 are turnably connected by means of pivot pins 24a, to a cross-bar 25. As shown in Fig. 2, said cross-bar 25 is provided with a depending lug 25a, having a vertical slot extending upwardly from the bottom wall thereof. The wire or member for manipulating the eyes, is designated by the reference numeral 18. At its upper end, and as shown in Fig. 2, said member 18 is provided with a bent portion 18a, whose upper end is located in the slot of the lug 25. The lug 25 and the top or vertical branch of the part 18a, are connected by means of a suitable pivot pin.

The dummy can be provided with trousers 12, which can be connected to the side walls of the body 9, by means of pins 14. Said pins 14 preferably have heads, to which the top of the trousers may be connected detachably if desired. Said pins 14 can pass through the material of the trousers.

The dummy is also provided with arm members, consisting of fabric strips 31 and 31a, which enclose masses of stuffing 33. The outer ends of the arm members are connected to hand members 34.

The dummy is also provided with a jacket 15, having arm portions 33.

As shown in Fig. 3, the hand H of the child can be applied, so that one finger enters the loop 27. This is preferably the third finger. The thumb and the first finger can hold the lateral finger-hold 19, which is connected to the bottom of the member 18.

When the jaw of the dummy is closed, the loop 27 is substantially at the bottom of the post 16, and the finger-hold 19 is located below the bottom 60 of the post 16.

The offset finger-hold 19 can be moved up and down, and it can also be turned, so as to move the eyes of the dummy up and down, or to cause them to move sideways, or to have any type of 65 desired rolling movement.

Hence the controls are conveniently assembled.

While the hand of the operator is in the position illustrated in Fig. 3, the post 16 can be turned so as to turn the head of the dummy, and the member 19 or the member 27 can be moved up and down relative to the post 16 and the member 18 can also be turned on its own axis. It is not necessary for the hand of the operator to shift in order to provide all the manipulations.

75 It will be noted that the planes of the offset

members 27 and 18 are substantially perpendicular to each other in what may be designated as the normal positions of the eyes and of the jaw. In said normal position the jaw member 20 is closed, and the eyes 23 have their pupils centrally located in the sockets which are provided in the front wall of the head of the doll.

Likewise, by making the body of the doll of a frame-like member having an opening therein, the parts can be assembled and manipulated conveniently.

It will also be noted that the control members 27 and 19 are located wholly within the opening of the frame-like body 9, so that the manipulating parts are not injured when the toy is handled or 15 packed.

In the preferred embodiment, I have shown the frame-like member 9 having an opening which extends through-and-through said member 9. However, it would be equivalent to provide said 20 member 9 with a recess instead of providing the same with a through-and-through opening.

Hence, whenever I refer to a frame-like body member having an opening therein, I include within the scope of the invention, a frame-like 25 body member having a recess.

In order to illustrate the parts more clearly, I have shown the width of the slot and the hollow post 16, as substantially greater than the thickness of the loop member 27, part of which is located within the hollow post 16 and part of which is exterior to said post 16. However, the loop 27 may fit fairly snugly in said slot so that when the loop 27 is turned relative to the vertical axis of the post 16, the post turns with said loop 27 in 35 substantial unison.

In certain aspects of the invention, it is not limited to the frame-like body.

I have shown a preferred embodiment of my invention, but it is clear that numerous changes 40 and omissions can be made without departing from its spirit.

I claim:

1. A dummy having a frame-like body member having an opening therein, a hollow post extending through the top wall of said frame-like body member and located above and below said top wall, said post being turnable on its axis relative to said top wall, a head located above said top wall and connected to the post so as to turn in 50 unison therewith, said head having a jaw member movably connected thereto, said head also having eye members movably connected thereto, a first operating member connected to said jaw member, the first operating member passing 55 through said hollow post and extending below said post, a second operating member connected to the eye members, the second operating member having an offset portion which extends laterally through a vertical slot which is provided 60 in a wall of said hollow post.

2. A dummy comprising a body, a hollow post turnably mounted on said body so that said hollow post can turn around its own axis, a head mounted on said body, said head having a movable jaw member and also having movable eye members, operating members located within said post and movable vertically relative thereto, said operating members being respectively connected to said jaw member and to said eye members so 70 as to operate the same, the operating member which is connected to the eye members being assembled with the post so that said operating member and the post turn in unison when the post is turned around its own axis.

3. A dummy comprising a body, a hollow post turnably mounted on said body so that said hollow post can turn around its own axis, a head mounted on said body, said head having a movable jaw member and also having movable eye members, operating members located within said post and movable vertically relative thereto, said operating members being respectively connected to said jaw member and to said eye members so as to operate the same, the operating member which is connected to the eye members being assembled with the post so that said operating member and the post turn in unison when the post is turned around its own axis, the last-mentioned operating member having a finger-hold which extends laterally through a vertical slot in said post.

4. A dummy having a body, a hollow post mounted on said body, said hollow post being turnable around its own axis, a head mounted on said hollow post, said head having a jaw member which is pivotally mounted to the head so that said jaw member can move up and down, said head also having eye sockets, eye members mounted in said sockets for turning movement about a vertical axis and for turning movement about a horizontal axis, said eye members having inwardly extending members connected thereto, said inwardly extending members being pivotally connected by means of vertical pivots to a lateral connecting member so that said lateral connecting member can be moved up and down and it can be also moved back and forth in the direction of its longitudinal axis, a first operating member passing through said hollow post and movable up and down relative to the post and connected to said jaw member, said first operating member having a lateral finger-hold

which extends through a vertical slot in the wall of the post, said finger-hold being partially located within the post and being partially located external to the post, so that the jaw member can be moved up and down by moving said first operating member up and down, and the post is turned in unison with said first operating member when said first operating member is turned around a vertical axis, a second operating member also extending through said hollow post, the second operating member having a lateral finger-hold which is located below the finger hold of the first operating member, the upper part of the second operating member being connected to said lateral bar, so that the eye members can be rocked up and down by vertically manipulating the second operating member, and the eye members can be rocked about a vertical axis by turning the second operating member around its own axis.

5. A dummy having a head, said head having a jaw member and also eye members movably connected thereto, independent operating members being respectively connected to said jaw member and to said eye members so as to manipulate the same.

6. A dummy having a head, said head having a jaw member movably connected thereto, said head also having eye members movably connected thereto, a frame-like body having an opening, a first operating member connected to said jaw member so as to manipulate the same, a second operating member connected to the eye members for manipulating said eye members, said operating members passing through the top wall of said body and having portions which are exposed in said opening.

MARTHA McCOWN.
